UNITED STATES PATENT OFFICE

171,461

CARPET UNDERLAY RUBBER MAT

Edward Stanley Robbins, Killen, Ala., assignor to Robbins Tire and Rubber Company, Tuscaloosa, Ala.

Application July 27, 1953, Serial No. 26,151

Term of patent 14 years

(Cl. D92—21)

To all whom it may concern:

Be it known that I, Edward Stanley Robbins, a citizen of the United States, residing at Killen, county of Lauderdale, State of Alabama, have invented a new, original, and ornamental Design for a Carpet Underlay Rubber Mat, of which the following is a specification, reference being had to the accompanying drawing, forming a part thereof.

I claim:

The ornamental design for a carpet underlay rubber mat, as shown.

EDWARD STANLEY ROBBINS.
